Primary Examiner — Janice Patyk(74) *Attorney, Agent, or Firm* — Armstrong Teasdale LLP(57) **CLAIM**

The ornamental design for a beverage pod, as shown and described.

DESCRIPTION

FIG. 1 is a bottom perspective view of a beverage pod showing our new design;

FIG. 2 is a side elevation view thereof;

FIG. 3 is a top perspective view thereof;

FIG. 4 is a top plan view thereof;

FIG. 5 is a bottom plan view thereof; and,

FIG. 6 is a cross-sectional view thereof taken along line 6-6 of FIG. 5.

The broken lines in the drawings show portions of the beverage pod that form no part of the claimed design.

1 Claim, 6 Drawing Sheets(56)
